UNITED STATES PATENT OFFICE.

DOWNES ELLAND NORTON, OF HAMPTON HILL, LONDON, ENGLAND.

MATCH HOLDER AND BOX.

Application filed May 28, 1921. Serial No. 473,390.

To all whom it may concern:

Be it known that I, DOWNES ELLAND NORTON, a subject of the King of Great Britain and Ireland, residing at Laurel Dene, 5 Hampton Hill, London, S. W., England, have invented certain new and useful Improvements Relating to Match Holders and Boxes, of which the following is a specification.

10 This invention relates to match holders and boxes and has among its objects to provide a match holder that may be used for holding matches having relatively short stems, and a convenient receptacle for the 15 holder and the matches for use therewith.

According to the invention a match box is provided advantageously of metal and having a flat form adapted for being carried in the pocket, the match box being adapted 20 for the reception of a holder by means of which the matches having short stems may be held while being struck, ignited and used and from which they may be expelled. The holder may be provided with a rod for the 25 purpose of expelling the stem of the used match, and this rod may be adapted to be withdrawn from the match holder in order that it may be used when desired for pipe cleaning, and the opposite end of the rod 30 may be adapted for use in pressing down the tobacco in the pipe.

The invention is illustrated in the accompanying drawing in which

Figures 1, 2, 3 and 4 are respectively front 35 elevation, end elevation, sectional front elevation and plan of a match box constructed according to the invention, while

Figures 5 and 5^a are diagrammatic detail views.

40 Figures 6 and 7 are end elevation and sectional front elevation of a re-fill receptacle or box for matches from which short stemmed matches may be filled into a match box such as described.

45 In carrying the invention into effect as illustrated in the accompanying drawings, I provide a metal match box or receptacle *a* advantageously of a flat form for being conveniently carried within the pocket, and

50 I provide means upon the receptacle for the reception of a stem or holder *b*. The stem or holder is provided of a cylindrical form and an axial hole is formed within this stem within which a cleaning rod *c* may be carried. The cleaning rod *c* may extend from one end to the other and at one end the stem

or holder *b* may be enlarged at *d* for being conveniently held, and with a curved face for pressing down the tobacco in the pipe while in an adjacent portion it may be conically formed and screw threaded for example with double or a treble thread, so that on being introduced through a hole or into a recess provided for its reception within the match box *a*, the holder *b* may be turned so that it may thus be firmly secured in position by the screw threads at *d*¹ engaging with corresponding screw threads on the match box or within a tube *e* mounted diametrically therein as hereinafter described. The end face of the head *f* may be concave to permit of the adjacent end of the cleaning rod *c* being forced inwardly. At the opposite end the holder *b* is conveniently provided with a recess or hole 75 adapted for the reception of a match having a reduced stem such as *g*. It will be understood that on the match being placed in position at the front end of the holder *b*, the end of the cleaning rod *c* is forced backwards. The holder may then be withdrawn from the match box and the match struck, and after the use of the match, the end of the cleaning rod *c* that protrudes beyond the head of the holder *b* may be forced inwardly, to expel the end of the match, and the holder *b* may then be applied or screwed 80 into position within the box or receptacle as indicated in Figure 3.

It will be understood that in the use of 90 such a holder, matches of short stem may be used and the match may be conveniently held in the hand without liability of burning the fingers.

The holder *b* may be used solely for the 95 purpose of holding matches for striking them against a prepared surface *h* upon one side of the match box, or against any other surface in which event a rod such as *c* may be mounted within the holder *b* in any suitable way, and the holder need not be provided so as to be separable from the rod.

According to one construction, however, as illustrated, I may provide the front or head part *d* of the holder *b* separable from the main part, and this part *d* I may adapt for connection with the end of the cleaning rod *c* as for example by means of a transversely disposed pin *i* passing diametrically through the front end or head part *d* of the holder and passing through an axial slot *c*¹ provided in the cleaning rod and the front

or head part may be adapted as illustrated in Figure 3 to be screwed into the enlarged part d^1 of the holder b , so that thus the front or head part d may be detached or unscrewed from the main part of the match holder and the cleaning rod c may thus remain connected with this front or head part for its effective use in cleaning the pipe; and after use the cleaning rod c may be returned to the holder b , and the front or head part of the holder may be screwed into position, so that the holder b may then be used for holding, and for striking matches, in the manner described.

15. It will be understood that the rear part of the holder may instead be separable from the main part.

The match box a may conveniently take a circular form as illustrated and be made of two almost symmetrical parts such as p and q having peripheral flanges j, j' , the peripheral flange j of one fitting within the peripheral flange j' of the other part, and forming a circular and enclosed cavity between them. Or instead the respective parts p and q may be made quite symmetrical and adapted as illustrated on an enlarged scale in Figure 5^a so that the edge of their respective flanges may contact with a scarf joint and be secured together by soldering or other means.

The box is advantageously provided with an integral tube e extending diametrically across from wall to wall and is secured to the peripheral wall by soldering or other means. At one end the bore of this tube e is advantageously screw threaded to correspond with the screw threads upon the part d^1 , so that upon the match holder being passed into the tube and the holder rotated, the screw thread on the holder engages the screw thread within the end of the bore and thus the holder is firmly secured in position. An opening for example at k may be made in the peripheral wall of the box so produced, which may be covered by a slide or closing plate l in any suitable way such as illustrated particularly in Figure 3. The slide l may be secured by means of a pin l^1 to a sliding spring plate l^2 adapted to contact with and slide beneath the peripheral wall of the box, and projecting parts and notches may be provided with a view positively to hold the slide l in its closed or open positions. It will be understood that the pin l^1 slides within a slot l^3 formed on the peripheral wall.

The match striking surface h may be mounted within a hole formed for its reception in the peripheral wall of the match box and it may be held in position by means of protruding flanges h^1 provided upon each side of the hole or aperture and the flanges h^1 may be diverted outwardly at the ends for the purpose of holding the striking sur-

face immovable. The striking surface h may be formed of a strip of hard steel having a roughened front face.

For the purpose of filling the box with matches and for withdrawing matches as they are required, the opening k is sufficiently long to permit of the matches, having short stems, to be allowed to fall out. It will be understood that both the inner and the outer peripheral walls are cut away to the same extent.

The inner part p (Figure 5) of the box or receptacle may be provided to rotate within the outer part q and for this purpose the holder previously passed into position in the box may serve as a stop to set the closed and open positions which may be conveniently done by providing a slot (or slots in opposite positions) in the outer peripheral wall within which the end of the holder may pass, as the inner part of the box is moved or rotated to open or close it.

Instead of providing the match box or receptacle of a circular shape in the manner described, it may be provided for example of a more or less oval or of any other shape, and a cylindrical hole or a hole of any other convenient shape, may be provided near one edge thereof for the reception of the match holder in substantially the same manner as hereinbefore described.

For the purpose of filling the match box or withdrawing the matches therefrom a spring cap may be applied at one or other end, instead of the sliding door described or any other form of closure may be provided.

Thus it will be understood that the invention is not limited to any particular form of the match box or receptacle.

Match boxes provided as hereinbefore described may be supplied with matches from receptacles o of a similar form as illustrated in Figures 6 and 7 advantageously made from cardboard or any other material, but with flat side walls and a circular peripheral wall, a hole such as r being provided in the peripheral wall which may be covered over with a strip n of tape or other material and caused to adhere and on the strip being removed the opening r may be brought into position over the slot k in the match box so that thus the matches from the receptacle may be allowed to fall into the match box. The hole r in the receptacle o may be provided of any suitable shape advantageously corresponding to that of the hole k and the match box a . By such means the match boxes can be readily charged and inasmuch as the matches are provided with short stems a box of comparatively small capacity will hold a considerable supply.

I claim:

1. A match box, means upon said match box for the reception of a match holder in position transversely through the box, and

- in combination a match holder and means respectively upon the match holder and the match box by which the match holder may be secured in its position therein, substantially as described. 5
2. A match box, an integral tube passing through the match box, and in combination with the said match box a match holder adapted to pass through the said tube, and means respectively upon the match box and the match holder for securing the holder in position on the match box, substantially as described. 10
3. A match box comprising an integral tube passing therethrough, and in combination therewith a match holder adapted to pass into position within the said tube, said match holder being provided with screw threads in determined position, and the said match box being provided with corresponding screw threads in determined position at the opening of the said tube, by which the said holder may be secured in position on the match box, substantially as described. 15
4. A match box of a substantially circular form comprising an integral tube passing diametrically through the said match box, and in combination a match holder adapted to pass through the said tube, and means re- 20
- spectively upon the said match holder and upon the said match box by which the holder may be secured in position on the match box, substantially as described. 25
5. A match box of a substantially circular form comprising an integral tube passing diametrically through the said match box and a slide mounted at the periphery of the said match box adapted to uncover a hole in the said periphery through which the matches may pass, in combination with a match holder adapted to pass through the said tube, and means respectively upon the said match holder and upon the said match box by which the holder may be secured in position on the match box, substantially as described. 30
6. A match box, means upon said match box for the reception of a match holder in position transversely through the box, and in combination a match holder, means respectively upon the match holder and the match box by which the match holder may be secured in its position therein, and means upon the said match holder for the reception of the match and for its expulsion therefrom after ignition. 35

DOWNES ELLAND NORTON.
